UNITED STATES PATENT OFFICE.

JAMES K. DALTON, OF NEWTOWN, AND MANDA MULLEN, OF CHILLICOTHE, OHIO.

DISH-WASHING MACHINE.

1,250,098.

Specification of Letters Patent. Patented Dec. 11, 1917.

Application filed August 13, 1917. Serial No. 185,981.

To all whom it may concern:

Be it known that we, JAMES K. DALTON and MANDA MULLEN, citizens of the United States, residing, respectively, at Newtown, county of Hamilton, State of Ohio, and Chillicothe, county of Ross, and State of Ohio, have invented certain new and useful Improvements in Dish-Washing Machines; and they do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in dish washing apparatus and consists of a simple and efficient device of this nature comprising various details of construction, combinations and arrangements of parts which will be hereinafter fully described, shown in the accompanying drawings and then specifically defined in the appended claims.

Our invention is illustrated in the accompanying drawings which, with the letters of reference marked thereon, form a part of this specification and in which:

Figure 1 is a side elevation.

Fig. 2 is a central vertical sectional view through our improved dish washing apparatus.

Fig. 3 is a sectional view on line 3—3 of Fig. 2.

Fig. 4 is a sectional view on line 4—4 of Fig. 2.

Reference now being had to the details of the drawings by letter:

A designates a cylindrical portion of the receptacle having a conical shaped lower portion B, said portion A having in the wall thereof a spiral way C. The said receptacle is supported upon legs D, having cross arms E connected thereto. The lower conical portion of the receptacle is provided with a depressed sink portion F from which an exit pipe H leads and which pipe is provided with a suitable valve I operated by the handle J. An inner dish holding receptacle, designated by letter N, is of a general conical shape, while its upper portion is of a cylindrical outline and has secured to its circumference brackets O carrying the anti-friction wheels R, which are adapted to

travel in the spiral way C as the receptacle N is given a rotary movement through the medium of the handle T connected thereto. Splashes, designated by letter S, and consisting of angle iron, are fastened to the inner surface of the receptacle N at intervals and at inclinations, and are provided for the purpose of agitating the water within the receptacle. The conical shaped receptacle N is provided with openings M, through which water is adapted to flow. In order to support the conical shaped dish holder above the bottom of the conical shaped portion B, a raised member G is placed upon the bottom of the receptacle B and serves to limit the downward movement of the dish holding receptacle.

In operation, the dishes are placed within the receptacle N, water being poured into the receptacle A to a sufficient height, and by operating the receptacle N through the medium of the lever T, the water may be agitated and the dishes thoroughly cleansed. After the dishes have been washed, the valve in the exit pipe may be opened and the water drained off and by pouring fresh water into the receptacle, after closing the valve, the dishes may be rinsed, and by opening the valve again the water may be drained off and the dishes quickly dried, after being treated by water of the proper temperature.

What we claim to be new is:

1. A dish washing apparatus, comprising a receptacle of cylindrical shape and having its wall formed into a spiral way, a dish holding member filling the space within said receptacle, having wheels journaled upon the outer circumference thereof and engaging said spiral way, and a handle fixed to said member within the receptacle.

2. A dish washing machine, comprising a receptacle having a cylindrical portion the entire wall of which is formed into a spiral way and the lower portion hopper shaped, a dish holding member, having a cylindrical portion extending the entire width of the interior of said receptacle, wheels journaled upon the outer circumference of the cylindrical portion of said member and engaging said spiral way, said member having its lower portion to conform to the hopper shaped portion of said receptacle and provided with perforations, splasher members projecting from the inner surface of the hopper shaped portion

of said member, a handle fixed to the member and positioned within the receptacle.

3. A dish washing machine, comprising a receptacle having a cylindrical portion, the entire wall of which is formed into a spiral way and the lower portion hopper shaped, a dish holding member, having a cylindrical portion extending the entire width of the interior of said receptacle, wheels journaled upon the outer circumference of the cylindrical portion of said member and engaging said spiral way, said member having its lower portion to conform to the hopper shaped portion of said receptacle and provided with perforations, splasher members

projecting from the inner surface of the hopper shaped portion of said member, a handle fixed to the member and positioned within the receptacle, the bottom of said receptacle having an upwardly projecting lug 20 adapted to limit the downward movement of said member.
